UNITED STATES PATENT OFFICE.

WALTER J. THOMAS, OF MEMPHIS, TENNESSEE.

PIPE WRENCH.

Application filed August 26, 1921. Serial No. 495,470.

To all whom it may concern:

Be it known that I, WALTER J. THOMAS, a citizen of the United States, residing at Memphis, in the county of Shelby and State 5 of Tennessee, have invented certain new and useful Improvements in Pipe Wrenches, of which the following is a specification.

This invention relates to improvements in pipe wrenches.

10 The primary object of the invention is the provision of a wrench designed in novel manner for use in pipe work and to effect the movements necessary in attachment or detachment of pipe connections and the like.

15 A further object of the invention is the provision of a pipe wrench of the above described character, in which the various parts have been durably constructed in cooperative manner, to provide an assembled wrench 20 structure capable of withstanding the strain incident to use; in this respect differentiating from the standard type of pipe wrench which is weakly constructed in parts necessitated by the peculiar movements which a 25 wrench of the type specified must have.

Other objects and advantages will be apparent during the course of the following detailed description.

In the accompanying drawings, forming 30 a part of this specification, and in which similar reference characters designate corresponding parts throughout the several views,

Figure 1 is a side elevation of the improved pipe wrench;

Fig. 2 is a rear edge elevation of the improved pipe wrench;

Fig. 3 is a side elevation, partly in section, showing the cooperative arrangement of the 40 various adjustable parts upon the wrench;

Fig. 4 is a cross sectional view, taken on the line 4-4 of Fig. 1;

Fig. 5 is an enlarged end view of the movable jaw, included in the pipe wrench;

45 Fig. 6 is an enlarged perspective view of a detail embodied in the improved pipe wrench.

In the drawing, wherein for the purpose of illustration is shown the preferred embodiment of my invention, the letter A designates a supporting structure having the movable jaw B attached thereto in adjustable relation by the adjusting means C.

The supporting structure A includes the 55 handle or hand engaging portion 10, upon

which is rigidly formed the head 11. A jaw element 12 is preferably attached in any approved manner to the supporting structure A, the same comprising the stationary jaw of the wrench structure. The head 11 is provided with a socket aperture 13 therein, adjacent the jaw element 12. A pair of lugs 14 are provided upon opposite sides 15 and 16 of the head 11, and immediately adjacent the rear arcuate edge 17 of said head 11. 60 Likewise, a pair of lugs 18 are formed upon the outer sides 15 and 16 diametrically opposite the lugs 14 with respect to the socket aperture 13. Certain end faces 19 and 20 of the lugs 14 and 18 respectively are provided in a plane extending radially of the socket opening 13, and for a purpose to be subsequently set forth.

The movable jaw B has been designed to overcome the deficiencies in the ordinary 75 type of pipe wrench. The same preferably comprises the jaw head 25 and the stem 26. The stem 26 is bifurcated to provide the spaced shank extensions 27 and 28, the space 29 intermediate said shank extensions 27 80 and 28 being of uniform width throughout the length of said shanks and sufficient to freely accommodate the width of the head 11. The upper and lower edges 30 and 31 of the shanks 27 and 28 are flattened, the 85 sides 32 and 33 of the shanks 27 and 28 respectively, being screw threaded, in cooperative manner, for engagement with the structure C. The article engaging surface 35 of the jaw head 25 is provided with the teeth 36 90 arranged in V-shaped manner as to their length, transversely upon the surface 35, the apex of each of said teeth 36 preferably pointing toward the forward edge 38 of the jaw head 25.

95 The adjusting means C, preferably comprises the reinforcing filler member 40 having its ends 41 arcuate in formation and struck from the same radius as the radius of the socket aperture 13. The filler member 100 40, in fact, is of the same width, as the width of head 11 and is adapted for disposition within the socket aperture 13, in such manner that its arcuate ends 41 contact the inner circumference of the socket 13, 105 for rotation therein in a manner to be subsequently set forth. A nut 43 of ring shaped formation is internally screw threaded for engagement with the screw threaded sides 32 and 33 of the shanks 27 and 28. The exter- 110

nal surface 44 of the ring shaped nut 43 is arcuated upon the same radius as the radius forming the arcuate aperture 13, in order that the ring nut 43 may be positioned in 5 the socket aperture 13 for oscillation therein.

In assemblage, the movable jaw B is so positioned over the supporting structure A that the teeth 36 thereof cooperate with the teeth upon the stationary jaw 12. In this 10 position, the shanks 27 and 28 forming the stem 26 will overlie the opposite sides 15 and 16 of the head 11. Preparatory to connection of the movable head B for adjustment upon the supporting structure A, 15 the filler member 40 must be inserted within the adjusting nut 43, and placed transversely through the socket aperture 13. The shanks 27 and 28 can next be positioned for insertion through the nut 43, and upon rotation 20 of said nut 43 within the socket aperture 13, the same will engage the threads 32 and 33 of the movable jaw shanks 27 and 28 and feed the movable jaw B toward the stationary jaw 12.

25 Arcuate springs 50 are provided for engagement upon the flat surfaces 31 of the shanks 27 and 28; said springs 50 being held by the lugs 14 in such manner that they extend forwardly to engage the shanks of the 30 movable jaw B above the axis or center of the socket aperture 13, thus normally rocking the movable jaw B so that the jaw head 25 thereof is in proximate relation with the jaw 12.

35 In operation, the improved pipe wrench is used in manner similar to the ordinary type of pipe wrench. The movable jaw B is positioned by the adjusting mechanism C so that the same may engage a piece of pipe 40 to be attached or detached. The springs 50 will of course, as hereinbefore described, rock the movable jaw C forward to normally grasp the pipe or article between the jaws of the wrench. Upon rotation of the pipe 45 wrench by the operator pushing upon the handle 10, the jaws will securely engage the said pipe to perform the desired work. Due to the V-shaped length of the teeth 36, a better grasp may be had upon a piece of 50 pipe in a predetermined length, than that which the ordinary arrangement of teeth is able to effect.

From the foregoing it can be seen that 55 a pipe wrench has been provided, in which the movable jaw B is capable of relative feeding longitudinally of the supporting structure A, as well as capable of oscillation in the head 11. In addition, the improved type of pipe wrench avoids the weaknesses of the ordinary type of pipe wrench. 60 This weakness in the ordinary type of pipe wrench is mainly due to the fact that but a single stem is provided upon the movable jaw B for engagement by the adjusting means thereon. It can be readily seen that the 65

plurality of screw threaded shanks 27 and 28 will provide a wrench capable of withstanding great stresses. The adjusting means C is of such a compact nature as to provide the exact movement of the movable 70 jaw B without any lost motion and can function in perfect manner.

Pipe wrenches of the type shown are sometimes of considerable weight and are apt to become broken due to the rough usage 75 to which the same are subjected. To prevent any breakage of the movable jaw B or its cooperating parts, the springs 50 will act as buffer elements. The lugs 18 will likewise prevent injury to the springs 50 due to excessive 80 oscillation of the movable jaw B upon its axis defined by the center of the socket aperture 13.

Various changes in the shape, size and arrangement of parts may be made to the 85 form of the invention herein shown and described, without departing from the spirit of the invention or the scope of the claims.

I claim:

1. A wrench, comprising in combination 90 a supporting structure including a jaw and socket opening, a movable jaw comprising a bifurcated stem to provide spaced shanks externally screw threaded on the outer sides thereof for overlying opposite 95 sides of said supporting structure, a filler member in said socket opening, and an adjusting nut within said socket opening and engaging said screw threaded shanks for straight line and arcuate movement of said 100 movable jaw.

2. A wrench comprising in combination a supporting structure including a handle, a stationary jaw, and having a socket opening therein, a movable jaw including a jaw 105 head and a pair of spaced shanks, said shanks being externally screw threaded, a filler member of the same width as said supporting structure and adapted for oscillatory movement within said socket opening, 110 a ring shaped adjustment nut for oscillatory movement within said socket opening and adapted for receiving said filler member and to engage the screw threaded shanks of said movable jaw, said shanks being positioned upon opposite sides of said 115 supporting structure.

3. A wrench comprising a stationary jaw including a supporting structure having a transverse perforation therein, a movable 120 jaw including a pair of spaced screw threaded shanks adapted for receiving said supporting structure of the stationary jaw in the space intermediate said screw threaded shanks, and an adjusting nut snugly disposed within said perforation for oscillation longitudinally of the shanks and rotation transversely thereof and engaging the 125 screw threaded shanks when so disposed

therein, whereby the movable jaw is adjustably positioned on the supporting structure against displacement.

4. A wrench, comprising a stationary jaw structure including a supporting extension having a cylindrical shaped aperture laterally disposed therethrough, a movable jaw including a pair of spaced screw threaded shanks adapted to receive said stationary 5 jaw extension therebetween to be disposed upon each side of the aperture therethrough, a nut snugly disposed for rotation within said aperture and engaging said screw threaded shanks for adjustment on the movable 10 jaw, said nut engaging the interior surface of said perforation at diametrically opposed points.

5. A wrench comprising a stationary jaw including a supporting extension having a 15 circular opening laterally therethrough, a movable jaw structure including a pair of spaced screw threaded shanks adapted for receiving the supporting structure of said stationary jaw therebetween, and an internally screw threaded socket nut adapted 20 for lateral placement in the circular opening of said stationary jaw structure for engaging the screw threaded shanks and whereby said nut may be rotated for adjusting said 25 movable jaw and prevent accidental displacement thereof.

6. A wrench, comprising a stationary jaw including a supporting structure having a

circular aperture laterally therethrough, a movable jaw structure including a pair of 35 spaced apart screw threaded shanks adapted for receiving said supporting structure therebetween, and to extend past the circular opening therein, a filler piece of substantially the same width as the width of said 40 supporting structure on the stationary jaw and adapted for snug fitting and rotary movement in the circular aperture intermediate said threaded shanks of the movable jaw, and a nut adapted for engaging the 45 screw threaded shanks and for snug rotary movement within the circular aperture of the supporting structure, and whereby the movable jaw may be adjustably positioned for longitudinal and arcuate movement with 50 respect to said stationary jaw.

7. A wrench, comprising a supporting structure including a jaw having a substantially cylindrical opening therein, a second jaw having a pair of screw threaded shanks 55 extending therefrom, and adjusting means oscillatively disposed in said substantially cylindrical opening and engaging said screw threaded shanks for movement of the second jaw, said adjusting means being so retained in the opening by said shanks as to 60 be the direct means of maintaining the shanks in proper position upon the supporting structure.

WALTER J. THOMAS.
